US00D811916S

(12) **United States Design Patent** (10) Patent No.: **US D811,916 S**
Lee et al. (45) Date of Patent: **** Mar. 6, 2018**

(54) **GAS DETECTOR**

(71) Applicant: **LG ELECTRONICS INC.**, Seoul (KR)

(72) Inventors: **Hophil Lee**, Seoul (KR); **Kyoungjoung Kim**, Seoul (KR); **Bonghui Kang**, Seoul (KR)

(73) Assignee: **LG Electronics Inc.**, Seoul (KR)

(**) Term: **15 Years**

(21) Appl. No.: **35/502,112**

(22) Filed: **Jul. 6, 2016**

(80) **Hague Agreement Data**

Int. Filing Date: **Jul. 6, 2016**

Int. Reg. No.: **DM/093723**

Int. Reg. Date: **Jul. 6, 2016**

Int. Reg. Pub. Date: **Dec. 16, 2016**

(30) **Foreign Application Priority Data**

Jan. 7, 2016 (KR) 30-2016-0000708

(51) **LOC (11) Cl.** **10-05**

(52) **U.S. Cl.**

USPC **D10/106.2**

(58) **Field of Classification Search**

USPC D10/46, 106.3, 106.6, 106.2, 53

CPC G08B 21/14; G08B 21/16

See application file for complete search history.
